UNITED STATES PATENT OFFICE.

LEE DE FOREST, OF NEW YORK, N. Y., ASSIGNOR TO GEORGE K. WOODWORTH, OF BOSTON, MASSACHUSETTS.

MAGNETIC DETECTOR.

No. 877,069.

Specification of Letters Patent.

Patented Jan. 21, 1908.

Application filed November 2, 1903. Serial No. 179,443.

To all whom it may concern:

Be it known that I, LEE DE FOREST, a citizen of the United States, and resident of the city, county, and State of New York, have 5 invented certain new and useful Improvements in Magnetic Detectors, of which the following is a specification.

My invention relates to an improvement in magnetic oscillation detectors for use in wireless signaling, and comprises the novel features which will hereinafter be described and particularly pointed out in the claims.

The object of my invention is to simplify and improve the construction of such devices 15 and particularly to avoid the variation in the intensity of signals produced by magnetic detectors due to the variation in intensity of the rotating magnetic field which is employed in certain types.

20 The accompanying drawings represent in a more or less diagrammatic manner constructions embodying the features of my invention.

Figure 1 represents a longitudinal sectional view of a portion of the detector and the connection of the aerial circuit therewith. Fig. 2 is an end view of the same device showing the connection of both the aerial and signal receiving or translating circuits.

30 Fig. 3 is a diagram illustrating the manner of connecting the various portions of the device in their respective circuits. Fig. 4 is a view similar to Fig. 2 representing a different method of connecting the translating circuit.

35 Figs. 5 and 6 are respectively plan and elevation showing a modified construction of the magnetic detector.

The above drawings illustrate constructions embodying my invention in forms which 40 are now preferred by me, said drawings being however of more or less diagrammatic character and therefore omitting details which are unnecessary to make clear the construction and operation intended.

45 In the operation of magnetic detectors employing a variable magnetic field, this field is most generally produced by the rotation of a permanent magnet, so that its poles move adjacent to an end of the core of the 50 magnetic detector. With such devices, experience has proved that the intensity of the signal produced depends in a measure upon the position of the poles of the magnet relative to the ends of the core. There is one 55 position in each half revolution of the magnet

in which the intensity of the signal is at a minimum and other positions substantially 90° removed therefrom in which the intensity of the signal is at a maximum, the positions between these two producing signals 60 gradually varying from maximum to minimum. It has also been found that the intensity of the signal is greatest when the pole of the magnet is approaching the core of the detector. One object of my invention is to 65 avoid this variation in the intensity of the signal produced, and to maintain the intensity of the signal constantly at a maximum. I secure this result by a construction of the detector, in which the core is divided up into 70 a number of parts which are so distributed with relation to the magnet that when the effect is at the maximum in one part it is at a minimum in another; the result being a maintenance of a substantially constant rate 75 of variation in the magnetic field as it affects a 1 of these parts of the core. The result may be said to be the production of a magnetic field which is constantly varying at a uniform rate and yet in which the sum total of 80 the magnetism in the detector as a whole remains substantially constant.

In the form of construction shown in Figs. 1, 2 and 3, I have divided the detector up 85 into a plurality of parts each of which is substantially an independent detector consisting of the cores C, the coils B through which pass the aerially induced waves, and the coils D which form a part of the translating circuit. These separate or individual detectors are grouped together in a ring, as viewed from an end or the position shown in Fig. 2, thus forming a substantially annular magnetizable member. The manner of wiring the individual parts is clearly shown in 95 Fig. 3, which does not correctly represent the relative position of these individual parts but represents what might be called the projection of these parts upon a plane, that is, as they would be if rolled out or in the flat. 100 This view is given in order to clearly show the manner of connecting the various parts or units of the detector. The coils B which immediately surround the cores C and through which the aerially induced waves 105 are passed, are connected in series between the antenna A and the earth E. The signal coils D are similarly connected in series in the translating circuit. This circuit is herein shown as provided with a telephone receiver 110

T, although any form of translating device may be employed.

The individual parts or units of the detector may have their coils connected in series, as shown in Fig. 3, or by groups in series parallel as desired. They might also be connected in parallel, although the arrangement shown in Fig. 3 is the one preferred by me.

10 In Fig. 4 I have shown a construction in which the coils B are connected in series or series parallel as desired, but the signal coil D' is a large coil which surrounds all of the detector units. The variable magnetic field 15 for such a detector may be conveniently produced in the manner and by the mechanism indicated in Fig. 1. In this case two magnets F and F' are employed, one at each end of the detector cores. These two magnets 20 are mounted upon a common shaft G which coincides with the axis of the detector, passing through the opening left at the center in the formation of the detector. This may be provided with means for rotating it of any 25 desired character. The double magnet herein shown produces a strong magnetizable effect upon the detector, and is efficient in this way. It will be seen that when a magnet is rotated with its poles adjacent the ends 30 of a detector of this construction, certain parts or units of the detector are all at times in favorable position for the production of a strong signal impulse, and no matter what the position of the magnet, some part of the 35 detector is at all times in the position of maximum effect. There will therefore be no variation in the intensity of the signal produced due to the position of the magnet, and one of the objections to the use of detectors 40 of the magnetic type is thereby avoided.

Figs. 5 and 6 illustrate a modified construction of magnetic detector within the scope of this invention. In this case the core C is in the form of a ring, and the coil R' 45 extends about this ring throughout its circumference, as does also the signal coil D' which forms a part of the translating circuit. The magnet F' is mounted with its axis coincident with the axis of the ring, the poles N 50 and S thereof preferably being formed, so as to embrace the ring. With this construction the location of the pole in the ring is constantly shifting, following the poles of the rotating magnet. The same effect as to the 55 maintenance of a constantly changing magnetic effect which is uniform in amount and at the same time with the maintenance of the sum of the magnetic conditions in the detector as constant, is obtained. With this form 60 of magnetic detector it is possible to rotate the magnet at any speed desired, as its rotation does not produce a click or signal in the telephone. The tendency of one part of the detector to produce a click is neutralized by 65 the tendency of another part to neutralize

this click, and consequently no sound is heard in the telephone receiver. I have found that such a device is very sensitive, and that there are no perceptible fluctuations in the strength of signals due to the position of the 70 magnet or magnets in their revolution.

It is evident that the constructions herein illustrated and described may be widely varied without however departing from the spirit of my invention. I do not therefore 75 wish to be limited to the exact constructions herein shown, but to claim the same broadly.

Having thus described my invention what I claim is:

1. In a magnetic oscillation detector, the combination with magnetizable means consisting of a plurality of magnetizable cores arranged annularly with respect to each other; of a magnet arranged substantially 85 concentric with respect to said magnetizable means; said magnet and magnetizable means being constructed and arranged to be relatively rotatable.

2. In a magnetic oscillation detector, the combination with magnetizable means consisting of a plurality of magnetizable cores arranged annularly with respect to each other; of means operable by received oscillations to vary the induced magnetization of 95 said magnetizable means; and a magnet arranged substantially concentric with respect to said magnetizable means; said magnet and magnetizable means being constructed and arranged to be relatively rotatable. 100

3. In a magnetic oscillation detector, the combination with a substantially annular magnetizable member, of a magnet arranged concentric therewith, the annular member and magnet being constructed to be relatively rotatable. 105

4. A magnetic oscillation detector comprising a plurality of cores and coils thereon grouped about a common axis, and a magnet mounted to turn upon a coincident axis. 110

5. A magnetic oscillation detector comprising a plurality of cores disposed about a common axis, separate coils for said cores connected in series, and a magnet mounted to turn upon a coincident axis. 115

6. A magnetic oscillation detector comprising a plurality of cores disposed about a common axis, separate but connected coils for the cores, a magnet shaft coincident with said axis, and a magnet at each end of the 120 cores having its poles adjacent the ends of cores which are diametrically disposed in the device.

In testimony whereof, I have hereunto affixed my signature this 8th day of October 125 1903, in the presence of two witnesses.

LEE DE FOREST.
